UNITED STATES PATENT OFFICE

CARL OSCAR JOHNSON, OF SPOKANE, WASHINGTON

DESIGN FOR A WALL INSET RADIOCABINET

Application filed April 15, 1931. Serial No. 39,493. Term of patent 7 years.

To all whom it may concern:

Be it known that I, CARL OSCAR JOHNSON, a citizen of the United States of America, residing at Spokane, in the county of Spokane and State of Washington, have invented a new, original, and ornamental Design for a Wall Inset Radiocabinet, reference being had to the accompanying drawings, forming a part thereof, in which—

Fig. 1 shows a front perspective view of the cabinet of my new design, and

Fig. 2 a front elevational view with the door in the open position.

I claim:

The ornamental design for a radio cabinet, as shown.

CARL OSCAR JOHNSON.
